UNITED STATES PATENT OFFICE.

THEODORE W. FOSTER, OF PROVIDENCE, RHODE ISLAND.

DESIGN FOR A HANDLE FOR BUTTON-HOOKS OR SIMILAR ARTICLES.

SPECIFICATION forming part of Design No. 33,239, dated September 25, 1900.

Application filed August 24, 1900. Serial No. 27,956. Term of patent 7 years.

To all whom it may concern:

Be it known that I, THEODORE W. FOSTER, a citizen of the United States, residing at Providence, in the county of Providence and State of Rhode Island, have invented and produced a new and original Design for the Handle of a Button-Hook or Similar Article, of which the following is a specification, reference being had to the accompanying drawings, forming part thereof.

Figure 1 is a side view of my newly-designed handle, showing the same attached to a button-hook, the blade of a paper-cutter being indicated in broken lines. Fig. 2 is a sectional view of the handle on the line X X of Fig. 1.

As shown in the drawings, the leading or material feature consists of the hexagonal form of the handle, terminating at the end connected with the button-hook or similar article in a scroll-decorated bulb and at the opposite end in an ornamented truncated pyramid having a rounded apex and a curved base at the juncture of the pyramid with the enlarged hexagonal part of the handle. At the end of the handle connecting with the ar-

ticle an annular bead forms the end of the handle. From this bead extends a bulbous body ornamented at the opposite sides with a foliated scroll ornament. The hexagonal body of the handle extends from the scroll-decorated bulb and gradually expands until the six sides merge into the pyramidal end of the handle, uniting with the pyramid in curved lines. The opposite sides of this end of the handle are ornamented with a foliated scroll ornament extending from the apex to the hexagonal sides of the handle and inclosing a rose ornament.

Having thus described my invention, what I claim as new, and desire to secure by Letters Patent, is—

The design for the handle of a button-hook or similar article herein shown and described.

In testimony whereof I have signed my name to this specification in the presence of two subscribing witnesses.

THEODORE W. FOSTER.
